UNITED STATES PATENT OFFICE.

MERLE J. WIGHTMAN AND HERMANN LEMP, OF HARTFORD, CONNECTICUT,
ASSIGNORS TO THE SCHUYLER ELECTRIC MANUFACTURING COMPANY,
OF CONNECTICUT.

DASH-POT FOR ARC LAMPS.

SPECIFICATION forming part of Letters Patent No. 367,081, dated July 26, 1887.

Application filed August 19, 1886. Serial No. 211,316. (No model.)

To all whom it may concern:

Be it known that we, MERLE J. WIGHTMAN and HERMANN LEMP, citizens of the United States, residing at Hartford, in the county of 5 Hartford and State of Connecticut, have invented a new and useful Improvement in Arc Lamps, of which the following is such a full, clear, and exact description as will enable any one skilled in the art to which it appertains to 10 make and use the same.

Our invention relates to means for steadyng the movements of the mechanism employed to feed the carbon in arc lamps, and it relates more particularly to a peculiar form of dash- 15 pot for accomplishing this purpose.

The invention consists of a dash-pot composed of two concentric cylinders, one of which is grooved at the surface of the contact and works within the other, this latter cylinder being recessed, so as to form a conical depression, 20 perforated at its apex, and having a ball resting in the aforesaid depression. The latter cylinder is provided with a link, which connects it to the pivoted frame-work of the lamp, 25 carrying the gearing by which the lamp is fed. The cylinders are located above said pivoted frame-work on the opposite side from the feeding-magnets.

In the accompanying drawing, forming part 30 of this specification, we have shown our invention as applied to an arc lamp, which has been patented to Hermann Lemp, November 3, 1885, No. 329,461; but it is not necessarily confined to use with any particular form of lamp; neither 35 is it confined to any particular location in a lamp, for it may be used anywhere in an arc lamp where it has the same function as described.

In the drawing the carbon-holder is design- 40 nated by the letter H, which intermeshes with the gearing G, located upon a frame-work, which is pivoted at a point, a, to the supporting-frame F of the lamp. This supporting-frame also carries the magnets M and D, which 45 are located in a main and derived circuit, respectively, and govern a core, to which an extension of the pivoted frame-work is loosely pivoted. The pivoted frame-work, carrying the gearing G, also carries a friction-wheel, W, 50 upon which bears a friction-brake, B, sup-

ported by a piece extending below said pivoted frame-work, which brake is adapted to be tripped off of said friction-wheel by a trip, T, which it comes in contact with as the frame-work oscillates to feed the carbon downward. 55

So far the construction and operation of the lamp described is the same as that shown in the patent above referred to. It will be observed in this construction that when the core is raised by the main magnet M, and the lamp 60 starts to feed by means of the derived-circuit magnet D, in which the current is now increased while it is decreasing in the main magnet M, there is a tendency of the carbon to feed suddenly, due to the gravitating of the carbon- 65 holder. This action is so sudden and instantaneous as to cause the carbons to come so near together that the light will flicker, and this will occur so rapidly that the main magnet will not have a chance to overcome it. It will 70 be noticed that this movement spoken of is independent of the feeding that takes place by means of the gearing, and that the present invention is designed only to obviate the irregular and sudden movement of the pivoted frame- 75 work, whose function is to govern the length of the arc within certain limits, the rest of the feed being controlled by the gearing.

Our invention consists in connecting a dash-pot, consisting of two cylinders, C and P, the 80 latter of which is grooved, in order to make it slide more readily in the cylinder C, to the pivoted frame carrying the gearing. These cylinders, constituting the dash-pot, are located on the opposite side of the carbon-holder from the 85 magnets, and are placed above the pivoted frame-work, the latter of which is connected to said pivoted frame-work by means of a connecting-link, l. The lower cylinder, P, forming the piston, is recessed at its lower interior 90 portion, so as to form a conical depression, and has also at its bottom a perforation, in which a ball or shot, constituting a valve, v, rests. The upper cylinder is secured to the fixed frame of the lamp by means of a screw, s, which 95 passes through the frame-work and through a hole in the end of the cylinder, which it seals, so as to prevent the admission of air. The shot is held by its gravity only over the perforation in the piston P, and allows the same 100

to descend readily, but retards its upward movement, as the air in the cylinder tends to force the valve more closely to its seat; but when the piston falls the air drives the ball 5 from its seat and permits the passage of the air into the cylinder. The shot and cylinders are not made to fit snugly, so that as the piston-cylinder is forced upward an escape of air takes place around the shot and between the 10 cylinders, thus resisting such movement to a certain extent, but not preventing the same.

The dash-pot having the functions described, it will be seen that it tends to restrain this sudden feed of the carbon, while it in nowise 15 interferes with the sensitiveness of the apparatus.

Having overcome the fault above referred to, it may be said that the action of the feed of the lamp is perfect, as the feed due to the gearing, which is controlled by the friction wheel and brake, may be regulated to any degree of 20 fineness.

We do not wish to confine ourselves to the exact construction of dash-pot described, nor 25 to limit the invention to any exact location of the dash-pot; but

What we desire to claim, and secure by Letters Patent, is—

1. The combination, in an arc lamp, of a dash-pot consisting of two concentric cylinders, as C 30 P, the latter constituting the piston and grooved at the surface of contact, a conical depression therein having a perforation in its apex, a globular body resting in said conical depression and covering said perforation, forming a valve, v, 35 and a link, l, pivotally connected with said piston and the lamp-regulating mechanism.

2. The combination, in an arc lamp, of a dash-pot for steadyng the movements of the same, consisting of a cylinder, C, secured to the frame 40 of the lamp, a piston, P, working in said cylinder, having a conical depression therein, a perforation in said piston, and a shot or globular body resting in said depression and closing said perforation by its own weight, and a connecting link pivoted to said piston and to the lamp-regulating mechanism.

In testimony whereof we have hereunto set our hands and seals, this 27th day of July, 1886, in the presence of the two subscribing witnesses.

MERLE J. WIGHTMAN. [L. S.]
HERMANN LEMP. [L. S.]
